(57) **CLAIM**

The ornamental design for a dispenser hanger, as shown and described.

DESCRIPTION

In a preferred embodiment, the nature of this product is as a hanger for a cleaner dispenser which is hooked onto a showerhead.

FIG. 1 is a top, left, front perspective view of a dispenser hanger embodying our new design;

FIG. 2 is a front elevational view thereof, the rear elevational view being a mirror image of the front elevational view shown;

FIG. 3 is a left side elevational view thereof;

FIG. 4 is a right side elevational view thereof; and,

FIG. 5 is a top plan view thereof.

The broken line representation of a lower section of the dispenser hanger in FIGS. 1-4 is shown for the purpose of illustration only, and forms no part of the claimed design.
